US00D474181S

(12) **United States Design Patent** (10) Patent No.: **US D474,181 S**
 Hong (45) Date of Patent: ** May 6, 2003

(54) **PORTABLE PERSONAL COMPUTER SYSTEM**

(75) Inventor: **Cuc Hong**, Cupertino, CA (US)

(73) Assignee: **Hewlett-Packard Company**, Palo Alto, CA (US)

(**) Term: **14 Years**

(21) Appl. No.: **29/147,383**

(22) Filed: **Aug. 29, 2001**

(51) LOC (7) Cl. **14-02**

(52) U.S. Cl. **D14/328**

(58) Field of Search **D14/328, 301, D14/314, 348, 356, 361-363, 365; D13/162, 184, 199; 361/680-686, 690-696**

(57) **CLAIM**

The ornamental design for a portable personal computer system, as shown and described.

DESCRIPTION

FIG. 1 is a perspective view showing the top, front, and right sides of my new design for a portable personal computer system.

FIG. 2 is a perspective view showing the left, front, and bottom sides of my new design for the portable personal computer system of FIG. 1; and,

FIG. 3 is a perspective view showing the top, left, and back sides of my new design for the portable personal computer system of FIGS. 1 and 2 without a handle extended.
